JOINT FOR SPRINGS

Filed May 17, 1922

INVENTOR.

Herbert S. Powell

BY

Thomas L. Wilder

ATTORNEY.

Patented May 26, 1925.

UNITED STATES PATENT OFFICE.

HERBERT S. POWELL, OF NEW HARTFORD, NEW YORK.

JOINT FOR SPRINGS.

Application filed May 17, 1922. Serial No. 561,730.

To all whom it may concern:

Be it known that I, HERBERT S. POWELL, a citizen of the United States, residing at New Hartford, in the county of Oneida and State of New York, have invented certain new and useful Improvements in Joints for Springs, of which the following is a specification, reference being had therein to the accompanying drawing.

10 My invention relates to a joint for springs, and I declare the following to be a full, clear, concise and exact description thereof sufficient to enable anyone skilled in the art to which it appertains to make and use the 15 same reference being had to the accompanying drawings in which like reference characters refer to like parts throughout the specification.

The object of the invention is to provide 20 a spring having a ball and socket joint that will permit the up and down motion of said spring without twisting or distorting it. Moreover, the ball and socket joint will allow the spring to retain its normal position, when assembled to the car, at all times. Furthermore, the parts of the spring can be replaced readily, thereby making it comparatively easy to repair the spring. The joint is constructed in such a manner that it 25 can be easily oiled.

The object will be understood by referring to the drawings, in which—

Fig. 1 is a side elevation of a spring, showing the novel joints;

35 Fig. 2 is a perspective view of a hood employed in the joint; the view being somewhat enlarged;

Fig. 3 is an enlarged view, showing a central vertical section of the joint;

40 Fig. 4 is an enlarged view, showing a central vertical section of a modified manner of forming the joint;

Fig. 5 is an enlarged vertical section of a joint used at the rear end of the spring;

45 Fig. 6 is an enlarged detail view, showing a perspective of a modified form of hood employed.

Referring more particularly to the drawings, the chassis of an automobile is represented by 1. Leaf springs 2 are employed to support the chassis at the front and rear portions. Said springs are arranged in parallel relation to each other and in sets of two. In this instance, the top leaf 3 of 55 each of the springs has its opposite extreme ends bent down at right angles, as at 4, 4.

A hood 5 is adapted to fit over the ends 3 and adjacent the bent part. Hood 5 is open at its bottom part and has lateral sides 6, 6 and an end wall 7. Wall 7 is adapted to 60 lie against the turned down end 4 of leaf 3.

Apertures 8, 8 are made in the opposite sides 6, 6 of hood 5 for the reception of a headed bolt 9 that with the aid of a nut is 65 adapted to hold hood 5 to the bent end 4 of leaf 3, as seen particularly in Fig. 3.

The top surface of hood 5 has formed theron a spherical hollow ball shaped dome 10 that is equipped with an elongated sector slot 11. Slot 11 is adapted for the projection of the shank 12 of headed bolt 13. Said shank 12 passes also through an aperture 15 in end 16 of the chassis 1 of the automobile.

75 End 16 is concaved, whereby to fit over the convex surface of dome 10. The two parts being held together by bolt 13 and nut 17, in such manner that the chassis end 16 can move more or less relative to dome 10, 80 which has the enlarged sector shaped slot 11 for this purpose. By the use of this joint at both ends of each spring 2, the spring will not be twisted or distorted but 85 will retain its normal position.

The rear end of each spring 2 is supported by a shackle or yoke 20 carrying a bolt 21 to which one end or other part of the chassis 1 is attached. The lower end of yoke 20 is mounted to the upper leaf 3 much 90 in the same manner that the front end is connected. A hood 5 is employed. The same is assembled to the rear bent over end 4 of leaf 3 and held in place by a bolt 9.

The end 16 of the chassis 1 is equipped 95 with a conduit 23 and reservoir 24 for the passage and storage respectively of oil, whereby to lubricate the parts of the joint. A cap 25 is screw threaded to the oil cup or reservoir 24.

100 Fig. 4 shows a modification of the device. Here the extreme end of the top leaf 26 is bent upward, as at 27 instead of downward, as in the former construction. The end wall 28 of hood 29 is adapted to rest 105 against the adjacent outer surface of end 27. The lateral sides 31, 31 of hood 29 extend downward and are equipped with apertures for the projection of a headed bolt 32 that holds the hood 29 in mounted position on the end 27 of leaf 26. A dome 34 110 is formed integral with hood 29 and has

an elongated sector slot 33 for the projection of the shank 35 of headed bolt 36 that unites the chassis 1 to the joint. An aperture 40 is formed in the flat surface of hood 5 29 for the projection upward of the bent end 27 of leaf spring 26.

Having thus described my invention what I claim as new and desire to secure by Letters Patent is:

- 10 1. In a joint for springs, a hood having a dome, said hood having lateral sides to aid in holding the same in a removable manner to the end of a spring and an end wall to aid in preventing end thrust, a member adapted to co-operate with said dome, whereby to prevent twisting or distorting of said spring and said member having an oil cup for the storage of oil to lubricate said joint.
- 15 2. In a joint for springs, a hood having a dome, said hood having lateral sides and an end wall to aid in holding the same in a removable manner to the end of a spring and an end wall to aid in preventing end thrust, a member adapted to co-operate with said dome, whereby to prevent twisting or distorting of said spring and said member having an oil cup for the storage of oil and a conduit for the passage of said oil to lubricate the joint.
- 20 3. In a joint for springs, a hood having lateral sides and an end wall to aid in holding the same in a removable manner to the end of a spring and to aid in preventing end thrust, a bolt to further aid in holding said hood, a member adapted to co-operate with said hood, whereby to pre-
- 25

- 35

vent twisting or distorting of said spring and said member having an oil cup for the storage of oil and a conduit for the passage of said oil to lubricate the joint.

4. In a joint for springs, a hood having a dome, lateral sides and an end wall formed on said hood to aid in preventing end thrust, a bolt adapted to project through said side walls, whereby to hold the hood to the end of a spring, a slot formed in the dome, a member having a concaved surface adapted to co-operate with said dome, a second bolt projecting through said slot in the dome and through the co-operating member, whereby to hold said parts together and said member having an oil cup for the storage of oil and a conduit for the passage of said oil to lubricate the joint.

5. In a joint for springs, a hood having a dome, side members and an end wall formed on said hood to aid in preventing end thrust, a bolt adapted to project through said side members, whereby to hold the hood to the end of a spring, a slot formed in the dome, a member having a concaved surface adapted to co-operate with said dome, a second bolt projecting through said slot in the dome and through the co-operating member, whereby to hold said parts together, and an oil cup in said member for the storage of oil, and a conduit in said members for the passage of the oil to lubricate said joint.

In testimony whereof I have affixed my signature.

HERBERT S. POWELL
